his ATTORNEY

UNITED STATES PATENT OFFICE.

HUBERT DALTON, OF STAMFORD, CONNECTICUT.

CURTAIN HOLDER.

Application filed October 21, 1926. Serial No. 143,037.

This invention relates to curtain holders and has for its primary object to provide a simple and inexpensive device easily applicable to the window frame or casing whereby the curtains or other draperies may be held or supported in spaced relation to the window opening in case full ventilation is desired and to prevent the curtains from being blown about and possibly soiled or otherwise damaged.

It is a more particular object of the invention to provide a device for this purpose which is so constructed, that it may be readily adjusted to operative or inoperative position relative to the window frame, and in the latter position thereof is inconspicuous and out of the way.

With the above and other objects in view, the invention consists in the improved curtain holder, and in the form, construction and relative arrangement of the several parts as will be hereinafter more fully described, illustrated in the accompanying drawings, and subsequently incorporated in the subjoined claims.

In the drawings, wherein I have disclosed several simple and practical embodiments of the invention, and in which similar reference characters designate corresponding parts throughout the several views,

Figure 1 is a perspective view illustrating the manner of application of my improved curtain holder to the window frame;

Fig. 2 is a plan view of the device;

Fig. 3 is an enlarged side elevation;

Fig. 4 is an end elevation of the device in an operative position;

Fig. 5 is a detail section taken on the line 5—5 of Fig. 3, and

Fig. 6 is a side elevation of the device in its inoperative position.

In the embodiment of the invention which I have selected for purposes of illustration, a bracket plate 5 is fixed at its ends to each side of the window frame or casing, said bracket plate extending vertically thereof and being preferably formed from a sheet metal stamping to provide a shallow longitudinally extending channeled rib 6, the open side of which is opposed to the face of the window frame when said bracket plate is attached. At its lower end, this rib is formed with an enlargement or boss 7 having an end wall positioned at an angle with respect to the plane of the bracket plate and provided with an opening 8 therein, the pur-

pose of which will be presently explained.

A lug 9 is riveted or otherwise suitably fixed at one of its ends to the upper end of the rib 5 and is engaged in one end of a channel shaped curtain holding arm 10, said arm being pivotally connected to said lug by the rivet or stud 11. To the other end of this channeled arm the flattened end of a cylindrical arm 12 is suitably connected by the pin or stud 13. In spaced relation to this connection 13 between the rod 12 and arm 10, the opposite side walls of the channeled arm are outwardly bulged or distended as shown at 14.

In the use of the device as above described, when it is desired to support the curtain at one side of the window opening, the channeled arm 10 is disposed in a horizontal position with respect to the bracket plate 5 and the free end of the rod 12 is engaged through opening 8 at the lower end of said bracket as shown in Fig. 3 of the drawings. It will be noted from reference to Fig. 2, that the pin 13 is of such length that it projects laterally from one side of the arm 10. Thus, after the curtain is draped over said arm as seen in Fig. 1 of the drawings, it cannot be blown inwardly beyond the arm and is also held or supported against being blown outwardly by air drafts through the window opening. In this manner the annoyance of the flapping curtain is obviated, and it is also protected against being soiled or otherwise damaged.

When it is no longer desired to use the device, the end of the rod 12 is disengaged from the opening 8 and said rod and arm 10 are permitted to swing downwardly from the lug 9 into alignment with each other. In this position of the parts, the boss 7 on the lower end of the bracket is received between the bulged or distended portions 14 of the side walls of the arms 10 so that as shown in Fig. 6, the collapsed device will lie closely adjacent to the window frame and will therefore, be inconspicuous and unobtrusive.

I have herein disclosed an embodiment of the invention which I have found to be entirely practical and satisfactory for the purpose in view. It will be seen that the device consists of relatively few parts of simple form and can therefore, be manufactured and sold at comparatively small cost. Since it is possible that the essential features of my present disclosure might also be em-

bodied in various other alternative structures, I reserve the privilege of adopting all such legitimate changes in the form, construction and relative arrangement of the 5 several parts as may be fairly incorporated within the spirit and scope of the invention as claimed.

I claim:

- 10 1. A curtain holder comprising an elongated bracket member adapted to be vertically positioned upon one side of a window frame and fixed thereto, said bracket member being formed of sheet metal with a longitudinally extending rib and at its lower 15 end being provided with an apertured boss constituting a socket, a curtain holding arm pivotally connected at one of its ends with the upper end of said bracket plate, and a rod pivotally connected at one end to the 20 other end of said arm and adapted to be engaged at its free end in said socket, to support said curtain holding arm in a substantially horizontal position with respect to the bracket plate.
- 25 2. A curtain holder comprising an elong-

gated bracket plate adapted to be vertically positioned and secured to one side of a window frame, said bracket plate being formed with a longitudinally extending rib terminating at its lower end in a boss provided 30 with an opening in the wall thereof, a lug fixed to the upper end of said rib, a channel shaped arm pivotally connected at one of its ends with said lug, a rod pivotally connected at one of its ends to the other end of said arm and adapted for engagement at its free end through said opening in the boss on the bracket plate to sustain said arm in a substantially horizontal position with respect to the bracket plate, and the opposite side walls of said arm adjacent to its pivotal connection with said rod being outwardly distended to receive said boss when the arm and rod are moved to a collapsed inoperative position in substantial alignment with each other.

In testimony that I claim the foregoing as my invention, I have signed my name hereto.

HUBERT DALTON.
